 5 Claims. (Cl. 57—98)

The present invention relates to a textile machine comprising spindles and strand-guides positively driven by shafts having a controlled differential rotation, the spindles and strand-guides being displaceable in relation to one another due to a "up-and-down" device. The machine eventually comprises at least one delivery cylinder which, as the case may be, forms part of a drawing frame. In the present text, the terms "spindles" and "strand-guide" must not be taken too literally and should be extended in meaning to include equivalent elements on various textile machines.

The above defined types of textile machines have been disclosed particularly in Belgium Patents Nos. 511,393; 530,373; and 556,117.

In certain known machines, the drives consist of one or several motors and mechanical transmission means such as gears, chains, cams, belts, etc. providing predetermined ratios between the various movable parts of the machine. In the event of a change in the operating conditions, it is necessary to change the gear ratios, exchange cams and displace chains. As a consequence, changes in the drawing, torsion or operating rates can only be carried out by steps and necessitate extended break-downs of the machine.

Certain known machines have reversible cams representing, for instance, the law of layer formation. These cams necessitate reversing devices which, by reason of the substantial resisting torque, may be the cause of errors due to slips (clutching) or due to breaks in the continuity (griffs wheels etc.).

It is obvious that in such machines a change in the profile of the cam, giving for instance the law of layer formation, is not possible during operation of the machine.

It is an object of the invention to obviate these disadvantages by doing away with most of the mechanical transmissions between the various parts of the machine, bringing about a simplification of the construction and a reduction in the volume as well as an appreciable increase in the flexibility. By the same token, it becomes possible to render the machine automatic and to control several machines from a central control station. To this end, in the machine according to the invention, at least most of the movable components of the machine are driven by individual driving devices each having an independent control chain sensitive to position or speed ordering signals, these ordering signals for the various independent control chains being prepared by a central coordinating member comprising adjustment means for the introduction of spinning data.

In an advantageous embodiment of the invention, particularly applicable to the textile machines according to the Belgian patents above mentioned, the ordering signals are electrical, the central coordinating means being an electronic device. This electronic device receives the spinning data and the parameters particular to the operation to be carried out (geometry of the bobbin), the data being introduced either manually, either previously prepared and stored on a support such as perforated cards or strips, magnetic tape, etc. creating speed and position ordering signals for the various components in the form of electrical voltages, images of the said speeds or provisions.

The advantage of this arrangement is that it is completely static and quite rapid.

In a particular embodiment, the individual driving devices driving the movable components of the machine are hydraulic motors combined with control devices responsive to the independent control chain signals, the hydraulic motors being preferably fed by a hydraulic generator group.

Other details and features of the invention will become apparent from the following description and the appended drawing which illustrates, by way of non-limitative example, a particular embodiment of the invention.

FIG. 1 is a diagram of the driving and control devices of the textile machine according to the invention;

FIGS. 2 and 3 are cross-sectional views of special form bobbins.

The invention is applicable to textile machines such as spinning looms, twisting mills, pre-spinning machines, such as those called "roving frames" etc. These machines comprise a great number of spindles mounted on a roving frame 1 and strand-guides on a strand-guide frame 2. The spindles are brought into rotation by means of a shaft 3 and the strand-guides by means of a shaft 4. The speed of the spindles differ from that of the strand-guides by a differential speed, shafts 3 and 4 being interconnected by gearing means 5 and 6 and by a differential 7 having a crown the rotation of which is controlled by a shaft 8. The roving frame 1 as well as shaft 3 and gearing 6 are supported by two jacks 9 and 10.

The textile machine may further comprise a delivering cylinder and one or several drawing cylinders. In FIG. 1, the driving shafts for the delivering cylinder and the feeding cylinder are numbered 11 and 12, respectively. An intermediate cylinder could be provided to serve as a predrawing cylinder.

The driving of the various shafts of the machine is achieved by hydraulic motors energized by a hydraulic generator group. The latter is formed by an electric cage motor driving a pump 14, a fly wheel 15 and a pump 16 connected to motor 13 by rigid couplings. Pumps 14 and 16 have a variable cylinder displacement. Pump 14 is provided with a device 17 for the adjustment of the cylinder displacement, the device being operated by remote control through the medium of a synchronous receiver 18. Pump 16 has a device 19 for adjusting the cylinder displacement, device 19 being actuated by another device 20 sensitive to the outlet pressure of pump 16 and automatically maintaining the pressure at the outlet of pump 16 constant regardless of its flow. Pumps 14 and 16 are fed by a motor fluid collecting into a discharge reservoir 21. Before being discharged into this reservoir 21, the motor fluid flows through a heat exchanger 22. Pumps 14 and 16 as well as their regulating and driving equipment are located in an engine room and are connected by means of piping to the motors of the machine in the spinning room. This separation between generator and motors is illustrated in the drawing by a dash line Z—Z, separating the parts of the textile machine which are located in the spinning room from those located in the engine room.

Pump 14 is mounted in parallel on two hydraulic motors 23 and 24 respectively driving shafts 3 and 4. Adjustment of their speed is obtained by adjustment on the cylinder displacement of pump 14, directed by means of a control on the control console, for instance a synchronous generator 25 connected to a synchronous receiver 18. The spindles and strand-guides constituting as a whole the group of elements using the most energy, one of the speeds of this assembly, in this instance the speed of the strand-guides or the shaft 4, has been selected as the basic speed of the textile machine. This basic speed is set at a

desired value by acting on the cylinder displacement of pump 14 by means of a synchronous generator 25 on the console.

However, when the hydraulic generator group is associated with other machines and mutual influence is to be avoided, all the pumps are self-regulating constant pressure pumps. In such a case, it is convenient to control by motor only one of shafts 3 or 4, the speed control preferably being obtained by adjustment of the cylinder displacement of the motor or by a servo-valve.

The speed of shaft 4 is measured by a speedometer 26, the measure voltage of which is fed into a central co-ordinating member, in this particular instance an electronic set 27, segregated in the drawing by a dash line contour. This electronic set is formed by various computing devices, among others, integration devices which also act as memory device; within these computing devices, certain parameters are capable of being regulated. The electronic set sends out position and speed ordering signals for the various movable parts of the machine.

The measure voltage delivered by the speedometer 26 is a signal proportional to the speed of the strand-guides. This signal is modified according to the twisting rate foreseen in a device 28 which, in the case where the speed of the strand-guide is proportional to the delivery speed, may be a potentiometer. A signal 29 appears at the output of device 28, the said signal being an image of the linear winding-on speed necessary to obtain the twisting rate desired. This signal, image of the linear winding-on speed, is also proportional to the ordering signals of the linear delivery speed and of the linear feeding speed. This condition is a feature of the spinning. Signal 29, because of its fundamental significance, serves as a basis for elaborating the various ordering signals applied to the independent control chains of the various individual motors of the textile machine.

Signal 29, an image of the linear winding-on speed, is modified according to the direct drawing rate under twisting to be provided in device 30, in this instant a potentiometer. A signal 31 appears at the output of device 30 which serves as an order for controlling the delivery speed necessary to obtain a desired drawing under twisting.

Signal 31, an order for the delivery speed, is compared in a comparison device 32 with the signal coming out of the speedometer 33 measuring the speed of shaft 11, driven by a motor 34, connected to the constant pressure of pump 16 through a servo-valve 35. The control chain for the control of the delivering cylinder driven by shaft 11 is thus formed by the comparison device 32 sensitive to the order signal 31, servo-valve 35, motor 34 and speedometer 33. In fact, the comparison device 32 delivers an error signal obtained by subtracting from the order signal 31 a measure signal 36 appearing at the output of the speedometer 33. The control of servo-valve 35 is a function of this error signal.

Signal 36 coming out of speedometer 33 is an image of the actual delivery speed. It is modified according to the drawing rate to be expected at the cylinders by means of a device 37, in this instance a potentiometer. At the outlet of this device 37, there appears a signal 38, which is an order for the feeding speed to be foreseen. The feeding cylinder, connected to shaft 12, is driven by a motor 39 joined to the constant pressure of pump 16 through a servo-valve 40. The control chain for the control of the speed of the feeding cylinder, driven by shaft 12, is thus formed of a comparison element 41 sensitive to order signal 38, servo-valve 40, motor 39 and a speedometer 42.

Signal 29, an image of the linear winding-on speed, is also applied to a control means made up by a computer comprising a function integrator-generator assembly 43, preceded or followed by a multiplicator 44 which makes it possible to take into account the direction of displacement of the "up-and-down" and of the winding pitch. A signal 45 appears at the output of the assembly of devices

43 and 44, signal 45 taking into account the length of wound thread and of the law of formation of a bobbin layer. In the instant example, the function generator in device 43 is conceived in such a manner that signal 45 gives the position of the thread in relation to the start of the layer being formed. A device 46 for the detecting of the limit height of the layers can send out a commutation signal 47 toward device 44, in such a way that the signal (winding direction upwardly or downwardly) and the value (magnitude of the winding pitch) of the multiplier introduced by device 44 may be accordingly modified. Commutation signal 47 serves, on the other hand, as counting impulse and consequently feeds also an integrator 48 of the number of layers.

By reason of the variation of the multiplicator at each layer end, signal 45, introduced by device 44, is an image of the cyclic variations of the instantaneous position of the thread as it is being wound in relation to the beginning of the layer. Signal 45 thus serves as an order signal for the movement of the "up-and-down" device. To this end, and eventually by means of a device 65 to be referred to again hereinafter, signal 45 is introduced in two comparison devices 49 and 50 respectively receiving the output signals of two position measuring devices 51 and 52 of two jacks 9 and 10 of the "up-and-down" device. Jack 9 is actuated from pump 16 through servo-valve 53 controlled by comparison device 49. Jack 10 is actuated from pump 16 through servo-valve 54 controlled by comparison device 50.

The integrator 48 of the number of layers delivers an output signal 55 proportional to the state of loading of the bobbin during the formation thereof, signal 45 making it possible, on the one hand, to modify certain adjustments in relation to the increase in the number of layers, for instance, the adjustment relative to the geometry of the bobbin, and on the other hand, to cause certain operations such as stopping of the machine at the time when a predetermined number of layers is reached.

Thus, in the case where the thread is wound in conical superposed layers, signal 55 is added to signal 45 in a device 65 in such a manner that a progressive spacing between the roving frame and the strand-guide frame is obtained at the same time as the cyclic movement of the "up-and-down" movement.

It is also possible to vary the "up-and-down" cycling movement, for instance by sending signal 55 back to a device 56, changing the height limits of the layers, as defined by detector 46. Such a measure makes possible, for instance, the formation of bobbins according to FIG. 2. On this figure, a spindle 70 supports conical layers 71, of different height. Another example of formation of bobbins is illustrated in FIG. 3. On this figure, the spindle 72 supports layers 73 which are either cylindrical or have a small conicity and of different height.

Other adjustments during the spinning are possible, even the law of formation of bobbins may be changed since all the parameters are defined by electrical elements.

The differential rotation between spindles and strand-guides, that is the rotation of the crown of differential 7, is controlled also by the central member of coordination. The crown of differential 7 is driven by an individual motor 57 through shaft 8. The independent control chain controlling the motor 57 is constituted by a comparison device 58, a servo-valve 59 and a measuring device, for instance, a speed measuring device 60. In order to elaborate an order signal for the differential rotation, the signal 45 may advantageously be used. In such a case, a function generator, for instance, an assembly 61 of an integrator and a multiplicator device may be mounted between the measuring device 60 and the comparison device 58. The integrator in device 61 allows transformation of the speed signal into an angle measuring signal. The latter is proportional, to a winding pitch, to the instantaneous position of the thread being wound. The factor due to the winding pitch is introduced by ad-

justment means provided in device 61 and modified in relation to the commutation signal 47. Thus, the output signal 62 is also an image of the cyclic variations of the instantaneous position of the thread as it is being wound in relation to the beginning of the layer being formed, as is signal 45. The comparison of these two signals 62 and 45 in device 58, results in an error signal 63 serving to control the servo-valve 54.

Eventually, an auxiliary modifying device 64 makes it possible to add an anticipation signal to order signal 45, for instance, a signal proportional to the derivative of the order signal 45. This makes it possible to compensate for the lagging effect which appears at high rotation speeds. This lagging effect is due to the fact that the thread does not follow a horizontal line between the strand-guide and the bobbin being formed but, rises towards the point of the bobbin when the spindles rise and fall towards the base of the bobbin when the spindles dip.

When the bobbin is finished, a measuring device 66 delivers a signal 67 particularly capable of controlling the stopping of the machine.

The above described example, although illustrating a particularly advantageous embodiment is not limitative and would particularly admit the addition of auxiliary devices known in themselves as well as elements that are somewhat different from those described and replacement thereof by other elements within the spirit of the appended claims.

I claim:

1. A spinning machine having spindles, rotatable guides moving around a bobbin and laying a thread thereon, a shaft driving the spindles, a shaft driving the thread guides, raising and lowering devices displacing the thread guides relative to the spindles, a differential connecting the shaft driving the spindles to the shaft driving the thread guides, feed and delivery rollers, driving devices for driving the shafts of the raising and lowering devices, the differential, the feed and delivery rollers, control devices for said driving devices, and an electronic controller fed with data and signals derived from one or more of the moving parts of the equipment whereby the driving mechanism is controlled by information fed to the electronic controller, the improvement wherein, said electronic controller comprises:

- (a) a first means for producing order signals, connections being provided between said means and said control devices controlling individual driving devices of said feed and delivery rollers, and said raising and lowering devices;
- (b) a second means for producing a signal which is proportional to the linear winding speed;
- (c) a first speedometer device measuring the velocity of said shaft driving said guides and connected to said shaft and to said second means;
- (d) a third means producing a signal modified in accordance with a desired rate of twist and connected to said second means and said control device controlling said driving device for said delivery roller;
- (e) a second speedometer device measuring the velocity of said delivery roller and connected to said control device associated with said delivery roller;
- (f) a fourth means converting the signal received from said second speedometer device to a signal modified in accordance with the drawing rate desired between said feed and delivery rollers and connected to said second speedometer device and said control device controlling said driving device of said feed roller;
- (g) a third speedometer device measuring the velocity of said feed roller and connected to said control device for controlling said driving device of said feed roller;
- (h) a functional integrator-generator device transforming said signal proportional to the linear winding speed to a signal representing the position of the thread relative to the start of the first layer, and con-

nected to said second means and said control devices for said raising and lowering devices;

- (i) a first and a second position-measuring device associated with said raising and lowering devices and connected to said control devices for said raising and said lowering device, respectively;
- (j) a detector for detecting the height limit of a layer supplying a control pulse when the height limit of a layer has been reached, and connected to said integrator-generator device;
- (k) a multiplying device, associated with said functional integrator-generator device and connected to said detector and responsive to the control pulse for taking into consideration the direction of displacement of said raising and lowering devices;
- (l) an integrator connected to said detector and supplying control pulses when the height limit of a layer has been attained; said integrator supplying an output signal proportional to the number of layers of thread wound on the bobbin during the formation thereof;
- (m) a tripping device for tripping a control signal as soon as the output signal of said integrator attains a predetermined value and connected to said integrator;
- (n) a device permitting the modification of the height limit of the layers defined by said detector and connected to and fed by said output signal of said integrator;
- (o) a signal feeding device the output of which is connected to said control devices of the raising and lowering devices and connected to said integrator-generator device and said integrator of the number of layers;
- (p) a function generator connected to a velocity measuring device located on said shaft driving a differential crown wheel between said drives of said guide and said spindle; said function generator and said functional integrator-generator device also being connected to said control device of said driving device of the shaft of said crown wheel;
- (q) an auxiliary modifying device in series with said integrator-generator device, permitting the taking into consideration of the differences between the theoretical and true spinning conditions.

2. A spinning machine comprising:

- a roving frame;
- spindles mounted on said roving frame;
- a shaft driving said spindles;
- a strand guide frame;
- rotatable guides mounted on said strand guide frame;
- a shaft driving said guides;
- a raising and lowering device displacing said strand guide frame relative to said roving frame;
- a differential connecting the shaft driving the spindles to the shaft driving the guides;
- a feed roller;
- a delivery roller;
- a hydraulic motor driving the shaft driving the spindles;
- a hydraulic motor driving the shaft driving the guides;
- a hydraulic motor driving said differential;
- a hydraulic motor driving said feed roller;
- a hydraulic motor driving said delivery roller;
- a hydraulic generator unit feeding said hydraulic motors and said raising and lowering device;
- a servo-valve between the hydraulic generator unit and said raising and lowering device;
- a servo-valve between the hydraulic generator unit and the hydraulic motor driving the differential;
- a servo-valve between the hydraulic generator unit and the hydraulic motor driving the feed roller;
- a servo-valve between the hydraulic generator unit and the hydraulic motor driving the delivery roller;
- a speedometer for the shaft driving the guides;
- a measuring device for the positions of the roving frame;
- a speedometer for the differential;

a speedometer for the feed roller;
 a speedometer for the delivery roller; and
 an electronic controller connected on the one side to
 said speedometers and measuring device and on the
 other side to said servo-valves.

3. The spinning machine of claim 2, in which the hydraulic generator unit comprises a pump feeding the hydraulic motor driving the shaft driving the spindles and the hydraulic motor driving the shaft driving the guides, a device for the adjustment of the cubic capacity of said pump, a second pump feeding the hydraulic motors driving the feed roller, the delivery roller and the differential and the raising and lowering device, and a device for the adjustment of the cubic capacity of said second pump.

4. The spinning machine of claim 3, in which the device for the adjustment of the cubic capacity of said first pump is connected to a measuring device responsive to the speed of a synchronous generator 25 and in which the device for the adjustment of the cubic capacity of the second pump is connected to a measuring device which is responsive to the pressure of the output of said second pump.

5. The spinning machine of claim 2, in which the speedometer for the shaft driving the guides is connected in the electronic controller to a potentiometer.
